UNITED STATES PATENT OFFICE.

ARGYLE CAMPBELL, OF CHICAGO, ILLINOIS, ASSIGNOR TO ENTERPRISE RAILWAY & EQUIPMENT COMPANY, OF CHICAGO, ILLINOIS, A CORPORATION OF ILLINOIS.

METALLIC CAR-ROOF.

No. 853,342.

Specification of Letters Patent.

Patented May 14, 1907.

Application filed October 30, 1905. Serial No. 285,083.

To all whom it may concern:

Be it known that I, ARGYLE CAMPBELL, a citizen of the United States, residing at Chicago, in the county of Cook and State of Illinois, have invented a certain new and useful Improvement in Metallic Car-Roofs, of which the following is a specification.

My invention relates to metallic car roofs.

The object of my invention is to provide a car roof which can be made of metal to possess a maximum of strength for a minimum amount of metal used, which can be easily made and installed and is not readily liable to get out of order.

15 It more particularly consists in the use of exterior carlines above the roof plates proper to give strengthening rigidity to the roof.

It also consists in details of construction which will be hereafter more fully described and claimed.

20 In the drawings, Figure 1 is a plan view partially broken away of a car roof embodying my invention in its preferred form. Fig. 2 is a sectional end view on line 2 of Fig. 1. Fig. 3 is a sectional end detail view on line 3 of Fig. 1. Fig. 4 is a detail view of the central portion of a carline. Fig. 5 is a detail view of a portion of the roof plates showing the ridge-pole and their attachment thereto. 25 Fig. 6 is an end detail sectional view of the upper edge of one side of the car and the means for attaching the roof plate and carline thereto.

It should be understood that the device of 30 my invention is applicable to the sides and ends of any ordinary car, one form of which is illustrated in Figs 2 and 3 of the drawings, in which the numeral 10 indicates the sides of a car having on their upper edges longitudinal members 11, the members being joined by any suitable means to the ends 12 of the car. Over such sides and ends of the car I place my metallic roof, consisting of a ridge-pole 13 made preferably in corrugated form running 35 lengthwise of the car at approximately its center, there being secured to this ridge-pole by bolts or rivets continuous longitudinal roof plates 15 extending from end to end of the car and overlapping the upper edges 11 of 40 the sides of the car in the downwardly turned portions 16, best shown in Fig. 6, the same being secured to the edges 11 of the sides of

the car by bolts, rivets or any suitable means, not shown. In order to give the roof thus constructed rigidity, I provide upon the outside 55 of the roof carlines 17 of the corrugated form shown in detail in Fig. 4. On these carlines 17 are flanges 18 adapted to be secured to the roof plates 15 by bolts or rivets passing through the holes 19 in the carline flanges and 60 the roof plates at suitable points. The outside ends of the carlines are bent downward over the outside edges of the roof plates 15 in the downwardly extending portions 20. These carlines may be secured at the edges of 65 the car to the upper edges 11 of the sides of the car by suitable bolts or rivets, not shown. In order to give the roof greater rigidity I form in the roof plates proper corrugations 22, as shown in detail in Figs. 1 and 3, these serving to stiffen the roof in the ordinary manner. 70 By this construction I provide a car roof without interior obstructions and I accomplish this without adding to the outside of the car a carline of a form which is at all in the 75 way.

Having thus described my invention, what I claim as new and desire to secure by Letters Patent is

1. In a metallic car roof the combination 80 with a ridge pole, of continuous metal roof plates secured to said pole and extending from end to end of the car, said plates having their edges supported directly upon the sides of the car, and a plurality of exterior carlines 85 supported upon and secured to said roof plates.

2. In a metallic car roof the combination 90 with a ridge pole, of continuous metal roof plates secured to said pole and extending from end to end of the car, said plates having their edges supported directly upon the sides of the car, and a plurality of exterior carlines supported upon and secured to said roof plates, said carlines extending across said 95 ridge pole from one side of the car to the other.

In witness whereof, I have hereunto subscribed my name in the presence of two witnesses.

ARGYLE CAMPBELL.
